WATCH STRAP WITH WATCH RETAINING LOOP

Max E. Westerman, Bronx, N. Y.

Application June 10, 1944, Serial No. 539,644

2 Claims. (Cl. 224—4)

This invention relates to a watch strap and more particularly to a watch strap having a watch retaining loop.

It is known to manufacture watch straps with watch retaining loops arranged on the straps at a position to permit the strap to be threaded through one of the bails of the watch and then through the loop, the loop thereby functioning to retain the watch in a fixed position on the strap. The watch is thus anchored to the strap and is prevented from sliding thereon or slipping off therefrom.

The prime object of my present invention centers about the provision of a watch strap provided with an improved watch retaining loop possessing the following characteristics and features:

(a) The loop is made to depend from the strap proper at the side edges of the strap and this is done without altering the structure or appearance of the strap. Thereby a free and fully open loop is obtained through which the strap may be readily threaded; the desired attractive appearance of the strap is maintained; and the loop itself is rendered inconspicuous and neat-appearing.

(b) The manufacture of the straps is not complicated or rendered more difficult by the addition of the watch retaining loop. The loop emerges from and depends from the side edges of the strap and is secured to the strap by the usual operation of stitching the edges of the strap. Thus the manufacturer of the strap is not materially altered and the simplicity of manufacturing steps as heretofore practiced is maintained.

To the accomplishment of this object and such other objects as may hereinafter appear, my invention is directed to the watch strap as sought to be defined in the appended claims and as described in the accompanying specification taken together with the following drawing in which:

Fig. 1 is a plan view of the underneath side of the finished strap showing the attachment thereto of a watch;

Fig. 2 is a side edge elevational view of Fig. 1;

Fig. 3 is a fragmentary view shown on an enlarged scale, depicting a step in the manufacture of the strap and particularly of the attachment of the loop thereto;

Fig. 4 is a view of Fig. 3 taken in cross-section in the plane of the line 4—4 of Fig. 3;

Fig. 5 is a view corresponding to that of Fig. 3 but showing a further step in the manufacture of the strap and the attachment of the loop thereto;

Fig. 6 is a view of Fig. 5 taken in the plane of the line 6—6 of Fig. 5; and

Fig. 7 is a perspective view drawn to an enlarged scale of the loop attached part of the strap showing the position assumed by the parts when the loop functions as a watch retainer.

Referring now more in detail to the drawing and having reference first to Figs. 1 and 2 thereof, the watch strap of the present invention comprises a two-ply watch strap S of conventional structure provided with a watch retaining loop L arranged on the strap in a position which may be referred to as a watch bail position, that is to say, in a position adjacent one of the bails 10 of a watch 12 which is adapted to be mounted on the strap, the other bail of the watch being indicated as 14. For mounting the watch 12 on the strap S, the strap is first threaded through the bail 10 which usually comprises a removable spring pin forming part of the watch case and is then threaded through the loop L after which the strap is threaded through the other bail 14 of the watch, resulting in the assembly depicted in Figs. 1 and 2 of the drawing.

The watch strap S, which, as stated, is of a conventional structure, is a two-ply formation having the upper ply 16 and the underneath ply 18 preferably made from a single strip of material and formed at one end into the buckle receiving tongue part 20 having the buckle pin perforations 22, and formed at the other end into a buckle holding part or fold 24. The buckle 26 is held within the fold 24 by the transverse line of stitching 28. The two plies 16 and 18 of the strap are sewn together by the lines of stitching 30 and 32 at the marginal side edges 34 and 36 and the stitching is also continued at the tongue end of the strap as at 38 and at the buckle end of the strap by the transverse line of stitching 40, a tongue keeper 42 being secured to and held between the plies of the strap by means of the transverse lines of stitching 28 and 40. As stated, this part of the strap construction is conventional.

The loop L is made to depend from the strap proper at the underneath ply 18 thereof from the side edges 34 and 36 of the strap and this is done without altering the structure or appearance of the strap. Thereby, as best shown in Figs. 5 and 7 of the drawing, a free and fully open loop is obtained through which the strap may be readily threaded. The desired attractive appearance of the strap is not only retained, but the loop itself is rendered inconspicuous and

neat-appearing, these latter features being best shown in Figs. 1 and 2 of the drawing. To accomplish this the loop L is made to comprise a thong or strip having a part 44 lodged between the plies 16 and 18 of the strap and having a loop part 46 emerging from and depending from the side edges 34 and 36 of the strap plies. To carry out these effects, the thong defining the loop L is attached to the strap plies 16 and 18 by the lines of stitching 30 and 32 at their marginal edges, as best shown in Figs. 5 and 7 of the drawing. In thus anchoring the loop L to the strap S, the usual steps of manufacturing the strap are followed through and thus the manufacture of the strap is not complicated or rendered more difficult by the addition of the loop.

In Figs. 3 to 6 of the drawing, I depict a preferred way of adding and anchoring the loop to the strap. The strap plies may be made of any desired material such as leather or a textile fabric; and in the form of the invention depicted in these figures a textile fabric is used. To produce finished side edges, this strap may be made from a length of material which in itself is made double ply by inturning or infolding the edges a and b of the material and having these edges meet in a median longitudinal plane c. This fabric may be rubberized on its inner face so that the infolded parts a and b may be adhesively secured to the outer face d of the strap. The thong forming the loop L consists of a strip of material, the ends 48 and 50 of which are placed in abutting relation at the median line c and the loop L is temporarily secured in this position by means of a piece of so-called Scotch tape 52, the purpose of which is to temporarily secure the loop in position at this step of the manufacture of the product. The result is the formation depicted in Figs. 3 and 4 of the drawing.

The strap material, after the buckle 26 is placed in position, is then folded over and the two plies of the strap are sewed together as described, the sewing of the strap plies by means of the marginal lines of stitches 30 and 32 being also effective as above described for sewing and thereby permanently attaching the loop portion 46 of the loop L to the side edges of the strap producing the assembly depicted in Figs. 5 and 6 of the drawing.

The method of making the watch strap of my present invention, the structure and functioning of the strap and the advantages flowing therefrom will now be fully apparent from the above

detailed description thereof. The loop L being made to depend from the side edges of the strap, there results a free and fully open loop through which the strap may be readily threaded, this feature being best depicted in Figs. 5 and 7 of the drawing. The loop is thereby attached to the strap without in any way changing the appearance of the strap either at its top ply or at its underneath ply. The loop itself, particularly when the watch is attached, is rendered inconspicuous and neat-appearing, as is depicted in Figs. 1 and 2 of the drawing. The loop being secured in position by the same lines of stitching which are used to secure together the plies of the strap may thus be attached without altering the customary manufacturing steps employed in making the strap.

While I have described the strap in the preferred form, it will be understood that some changes may be made therein without departing from the spirit of the invention defined in the following claims. As stated, for example, the two plies of this strap may be made of any desired material, such, for example, as cloth or leather, or the top ply may be made of one material such as leather and the bottom ply of another material such as cloth or a lining; and when leather is used the inturning of the edges of the plies would be dispensed with. Other obvious changes may be made in the construction.

I claim:

1. A watch strap with a watch retaining loop comprising, a two-ply watch strap formed at one end into a buckle receiving tongue and at the other end into a buckle holding fold, the two plies of the strap being sewn together by stitching including stitching along their marginal side edges, and a watch retaining loop depending from the underneath ply of the strap at a watch bail position of the strap, the said loop consisting of a flexible thong having its opposite ends lodged between the strap plies and having its loop part emerging from and depending from the side edges of the strap plies, the said thong being attached to the strap plies by the stitching at their marginal edges, which stitching is through the material of the flexible thong.

2. The watch strap of claim 1 in which the opposite ends of the thong are also adhesively secured to the inner face of the underneath ply portion of the strap, the thong being permanently secured to the strap by the marginal edge stitching.

MAX E. WESTERMAN.
